(Continued)*Primary Examiner* — Dana Meyrow*(74) Attorney, Agent, or Firm* — Carolyn S. Powell; Melissa Gartstein Krasovec**CLAIM**

The ornamental design for a bottom dispensing container or the like, as shown and described above.

DESCRIPTION

FIG. 1 is a perspective view of a bottom dispensing container;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken lines in the drawings illustrate the portions of the bottom dispensing container that form no part of the claim.
